UNITED STATES PATENT OFFICE.

WILLIAM T. TREADWAY, OF ST. LOUIS, MISSOURI, ASSIGNOR TO UNIVERSAL ACCOUNTANT MACHINE COMPANY, OF ST. LOUIS, MISSOURI, A CORPORATION OF MISSOURI.

KEYBOARD FOR CALCULATING-MACHINES.

SPECIFICATION forming part of Letters Patent No. 722,438, dated March 10, 1903.

Application filed December 10, 1902. Serial No. 134,654. (No model.)

To all whom it may concern:

Be it known that I, WILLIAM T. TREADWAY, a citizen of the United States, residing at St. Louis, Missouri, have invented a certain new and useful Improvement in Keyboards for Calculating-Machines, of which the following is a full, clear, and exact description, such as will enable others skilled in the art to which it appertains to make and use the same, reference being had to the accompanying drawings, forming part of this specification, in which—

Figure 1 is a vertical sectional view through the front portion of a calculating-machine, showing my improved keyboard in position thereon. Fig. 2 is a fragmentary top plan view, partly in horizontal position; and Fig. 3 is a detail view in vertical section, showing the parts in a changed position.

This invention relates to a new and useful improvement in keyboards for calculating-machines of that type shown and described in United States Letters Patent No. 654,181, granted to Frank C. Rinsche July 24, 1900.

In the accompanying drawings I have not shown all of the elements entering into the construction of calculating-machines, but have illustrated only those which directly co-operate with my improved form of keyboard.

It is the object of my present invention to construct the keyboard in such manner that the sliding plates, which co-operate with a series of keys, will be locked in their operated positions, so as to hold the operated key in a depressed position, the remaining keys of that series being locked in an elevated position.

Another object is to compel a full operation of a key before the associate parts controlled thereby are set in an adjusted position.

Another object is to simplify the construction of keyboards of this character and so arrange the parts that their operation is positive to an extent whereby in the event of breakage of springs the keyboard would not be placed out of commission.

With these objects in view my invention consists in the construction, arrangement,

and combination of the several parts, all as 50 will hereinafter be described and afterward pointed out in the claims.

In the drawings, 1 indicates the base-casting of a calculating-machine, which is preferably supported by cushions 2, and upon 55 which casting is arranged a casing 3, provided with suitable openings, through which project certain parts of the machine. The keyboard is removably supported upon the forward ends of right and left hand frame- 60 plates. This keyboard consists of a top plate 9, an intermediate plate 10, and a bottom plate 11, said plates being provided with openings for guiding the shanks 12 of the keys in their movements. Suitable spacing-posts are 65 provided between these plates 9, 10, and 11. Each key - shank is provided with a cam-shaped opening 13, which has a bearing-face 14 for coöperating with the pins 17, hereinafter described.

15 indicates sliding plates which are normally held in a rearward position by springs 16. These sliding plates, as shown in Fig. 2, are recessed on their opposite edges to receive the key-shanks, and said sliding plates 75 are furthermore provided with the pins or projections 17, which coöperate with the face 14 of the opening 13, formed in the key-shanks. The key-shanks are held elevated by means of springs 18, which springs are secured at 80 their upper ends to projections formed on the transverse plates 19, which are arranged under the intermediate plate 10.

22 indicates a locking-detent, there being one of such detents pivotally connected to 85 each of the sliding plates and near their forward ends. These detents each have cam-faces 23, a locking-hook portion 24, and a forwardly-extending finger 25, the latter providing means for the attachment of a spring 90 26. The locking-hook portion 24 coöperates with a bar 27, said bar being shown as having a groove milled therein; but it is obvious that other forms of fixed projections could be provided with which the locking-hook portions 24 could coöperate.

Cam-faces 23 coöperate with fingers 50, which fingers are mounted upon a rocking

frame 47, which frame is operated whenever the main shaft 6 is rocked by connections not shown in these drawings or by the manipulation of the total-key 42.

- 5 28 indicates slide-bars which are provided with stops 29 for coöperating with a depressed key, said slide-bars being pulled forwardly under the action of springs 29^a when the main shaft 6 is rocked, usually by means of a 10 hand-lever or operating-handle upon one end thereof and external the casing of the machine. The slide-bars referred to are restrained from forward movement by means of latch-pins 33, which pins are mounted upon 15 bell-crank levers 32. The upwardly-extending member of each bell-crank lever is in the path of a coöperating sliding plate, and by this construction whenever a key in a series is depressed the sliding plate is positively 20 moved forwardly, so as to raise the bell-crank lever referred to and release the slide-bar 28, identified with the series of keys under consideration. Unless the locking-hook portion 24 rides beyond its coöperating bar 27 it follows that when the operator releases the 25 depressed key it will return to its normal position under the impulse of its spring. Thus if a key is not fully depressed, while the slide-bar 28 might be temporarily released, said 30 slide-bar will be prevented from moving forwardly when the handle is operated, because the controlling elements therefor—to wit, the latch-pin, the bell-crank lever, the sliding plate, and the series of keys common there- 35 to—are restored to normal position before the handle is operated. However, when the key is fully depressed it effects the setting up of a stop in the path of one of the pins 29 and at the same time the sliding plate is 40 moved forwardly to raise the latch-pin 33 through the medium of the bell-crank lever 32, and finally the hook portion 24 engages the bar 27 and holds the parts in their set position. This set position of the parts is shown 45 in Fig. 3, wherein it will be seen that one of the projections 17 occupies a position at the upper end of the curved cut-out portions 13, formed in the operated key-shank, and all of the other keys will be held by means of the 50 horizontal slots 30 in their rearmost faces engaging with the sliding plate 15, while said plate 15 will engage the notch 31 of the key which is thus depressed, so that none of the other keys of that series can be depressed 55 when the sliding plate occupies its forward position, as described.
- When the operating-handle is manipulated to move the slide-bar 28 forwardly against the stops set up by the operated key, said 60 operating-handle also rocks the frame 47 rearwardly, and in so doing the finger 50 engages the cam-face 23 of the locking-detent, raising the locking-hook portion thereof out of engagement with the bar 27, which permits the 65 sliding plate to be restored to its home position under the impulse of its spring. If for any reason this spring refuses to act, the fin-

ger 50, after raising the detent 22, will positively restore the sliding plate, which sliding plate will positively restore the depressed key should its spring 18 refuse to act.

It will be observed by referring to Fig. 1 that the cut-out portion formed in the key-shank is of such dimensions that when the keys are home the projections 17 can play freely therein without frictional contact. Of course when a key is depressed there is frictional contact between the projections 17 and the rearward face 14 of the curved opening, due to the cam action in moving the sliding plate forwardly. 80

I am aware that minor changes in the construction, arrangement, and combination of the several parts of my device can be made and substituted for those herein shown and described without in the least departing from 85 the nature and principle of my invention.

Having thus described my invention, what I claim as new, and desire to secure by Letters Patent, is—

1. In a machine of the character described, 90 the combination with a depressible key having an opening with a cam-face, and locking-notches in the forward edge thereof, of a sliding plate having a lateral projection for coöperating with the forward face of said opening, whereby, when the key is depressed, the plate is moved longitudinally, and when the key remains in an elevated position and the plate is moved longitudinally said plate will lock said key in its elevated position; sub- 95 substantially as described.

2. The combination with a key-shank provided with a locking-notch and an opening having a cam-face, of a sliding plate provided with a projection for coöperating with said 105 cam-face and locking-notch whereby, when the key is depressed, the plate is moved longitudinally and when the key remains in its elevated position it is locked in such position by the longitudinal movement of the plate, 110 and means for restoring the plate which effects the raising of the key; substantially as described.

3. The combination with a series of keys whose shanks are provided with curved cam-shaped openings and locking-notches in one edge thereof, of a sliding plate common to said series of keys and provided with projections coöperating with said cam-shaped openings, a spring connected to said sliding plate, 120 springs for each of the keys, and a locking-detent carried by said sliding plate; substantially as described.

4. The combination with a longitudinal series of keys, each of which is provided with 125 a cam-shaped opening and shouldered recesses, of a notched plate provided with means for engaging with a face of said cam-shaped opening and which is slid longitudinally into the recesses of the key-shanks for 130 limiting the vertical movement of said shanks; substantially as described.

5. The combination with a series of keys, of a sliding plate coöperating with notches in

one edge of said keys, a locking-detent co-operating with said sliding plate, a cam-face on said detent, a rocking frame coöperating with said cam-face, and means for rocking 5 said frame; substantially as described.

6. The combination with a series of keys having notches in one edge thereof, of a sliding plate coöperating with said notches, a spring-held locking-detent carried by said 10 sliding plate, a cam-face on said detent, and means coöperating with said cam-face for moving said detent out of locked position; substantially as described.

7. The combination with a series of keys 15 having cam-shaped openings in their shanks and notches in the forward edges of said

shanks, of a sliding plate and engaging means on said plate coöperating therewith, a locking-detent 22 on said sliding plate, said detent having a cam-face 23, a locking-shoulder 20 24, and a projection 25, a spring 26 coöperating with said projection 25, and a bar 27 coöperating with the locking-shoulder 24; substantially as described.

In testimony whereof I hereunto affix my 25 signature, in the presence of two witnesses, this 6th day of December, 1902.

WILLIAM T. TREADWAY.
